UNITED STATES PATENT OFFICE.

NICK SOLTESZ, OF TOLEDO, OHIO.

RAIL CONNECTER.

Application filed February 16, 1925. Serial No. 9,395.

To all whom it may concern:

Be it known that I, NICK SOLTESZ, a citizen of the United States, and a resident of Toledo, in the county of Lucas and State 5 of Ohio, have invented a new and useful Rail Connector, which invention is fully set forth in the following specification.

This invention relates to devices for connecting together the end portions of rails in 10 such a manner as to support them and maintain their longitudinal alignment.

The end portions of rails are ordinarily connected together by fish plates which engage the sides of the adjoining rails and are 15 secured thereto by bolts and nuts, the extreme ends of the rails being spaced a slight distance from each other to permit unimpeded expansion and contraction of the rails under different weather conditions. While 20 to a certain degree this manner of connecting the rails is satisfactory, nevertheless there is considerable opportunity for improvement, especially to provide a connection which eliminates one of the foremost 25 existing objections, i. e., sagging of the joint when subjected to extraordinarily heavy loads. Another cardinal objection to the usual fish plate connection resides in the fact that holes for bolts must be bored in 30 both the rails and plates and in securing the nuts to the bolts, all of which requires considerable time and is relatively expensive. It has also been observed that owing to frequent jars and vibration the nuts have a 35 tendency to become loose, which is obviously dangerous to both life and property.

Objects of this invention are to eliminate the necessity of using the ordinary fish plates requiring bolts and nuts to secure the 40 end portions of rails together; to provide a simple and inexpensive device for securing rails together, which facilitates the assembling operation and reduces the time and trouble occasioned by methods at present 45 in use; and to provide a rail-connecting device having the new and improved features of construction and arrangement herein-after described.

The invention is shown by way of illustration in the accompanying drawings, in 50 which,—

Figure 1 is a top plan view of the device showing the manner in which the rails are connected. Fig. 2 is a transverse section on the line 2—2 of Fig. 1; Fig. 3 is a perspective of the end portion of a rail, and Fig. 55

4 is an end elevation of the connector and rail similar to Fig. 2.

The embodiment of the invention shown for purposes of illustration comprises a 60 connector A, which may be secured to the cross ties B on the railway road bed by spikes 1, extending through apertures 2 in the connector. Formed in the connector A are oppositely arranged sockets or recesses 65 to receive the end portions of the rails 3 to prevent sagging and lateral movement thereof, although sufficient clearance is allowed between the ends to permit unobstructed expansion as well as contraction of 70 the metal under different weather conditions. An outstanding feature of the invention consists in the elimination of bolts and nuts in connecting the rails in order to overcome the objections apparent in existing connecting means of which I am aware. 75

Referring more particularly to the drawings, the connector A comprises a longitudinally elongated base plate 4 for supporting the end portions of the adjoining rails 3 80 to thereby prevent sagging of the joint, which sagging is objectionable and particularly noticeable in fish plate connections after a comparatively short time. Along one edge of the base plate is provided an 85 integral flange 5 which extends from such edge in gradually increasing spaced relation to the plate to adapt it to engage over one of the base flanges of the rail 3. Integral with and extending inwardly from the 90 base plate, and disposed at approximately right angles to the base plate is a side plate 6 whose length is approximately two-thirds 95 of the strip 5. Apertures 2 are formed in the strip 5 at suitably spaced intervals through which spikes may be driven into the ties B for securely holding the connector thereto.

Formed centrally of the side plate 6 and projecting laterally therefrom is an integral 100 web 7, and integral with the web 7 is a side plate 8, which is similar in shape to the side plate 6. The side plate 8 may be somewhat shorter than the side plate 6 and the plates are arranged to engage opposite sides of the 105 rail 3, the lower part of the rail resting on the base plate 4 and the upper part engaging the upper surface of the plates while the web of the rail projects into the space 7a between the plates. By constructing the 110 outer side plate 6 of substantial length, it will be apparent that the outward thrust of

the vehicle wheels on the track will be counteracted.

As most clearly indicated in Figure 3, the ends of the rails are recessed at 9 so that the upper and lower portions of the rail may extend, respectively, above and beneath the web 7, and the extreme ends of the rail may thus be separated sufficiently to permit expansion of the metal under relatively warm weather conditions. The web 7 also constitutes a stop for limiting the longitudinal movement of the rails in the connector A. For securely holding the side plate 8 in place an integral inturned lip 10 of substantially the same length as the plate 8 is formed on the adjacent edge of the base plate 4 and engages over the lower outwardly flanged or floor portion 8a of the plate 8. Holes 2 are formed in the lip 10 to receive the holding spikes.

Altho the connector A may be formed with the parts in the position indicated and thereafter the sockets cored out, for the purpose of reducing the manufacturing cost the connector is preferably cast in such a manner that the base plate 4 extends outwardly at substantially right angles to the side plate 6. Thereafter the base plate 4 may be turned inwardly against the lower portion of the side plates and the lip 10 may then be turned over the side plate 8, as indicated in Fig. 2. In order to reduce the bearing surface between the rails 3 and connector A, a longitudinal groove 11 may be formed in the side plate 6.

In securing the rails to the connector A, the rails may first be beveled, as at 12, so that they may be inserted more readily into the sockets in the connector. The connector may not be attached to the cross ties B in the assembling operation so that after the rails 3 have been inserted into the sockets (assuming the opposite ends of the rails engage fixed abutments) the connector may be pulled or forced inwardly by a suitable tool until the rails are brought into alignment when the ends thereof extend deeply into their respective sockets, the extremi-

ties being brought into close proximity to the web 7. Thereafter the spikes 1 may be driven into the cross ties B in order securely to hold the rails and connector in assembled relation.

While I have described my improved rail connector in more or less detail to comply with the requirements of the statute, it is nevertheless desired that this detailed description be considered merely as illustrative and not limiting, and it is to be understood that changes and modifications may be made by those skilled in the art without departing from the spirit of the invention especially as defined in the appended claims.

What I claim is:

1. A rail connector comprising a base plate, a pair of side plates, one of said plates being integral with said base plate, an inwardly extending lip on said base plate in clamping relation with the other side plate, and a web integral with said side plates.

2. A rail connector comprising a base plate, a pair of side plates, one of said plates being integral with said base plate, an inwardly extending lip on said base plate, in clamping relation with the other side plate, and a web integral with said side plates, said web being of such dimensions that the wheel engaging portion of the rail is disposed thereabove.

3. The combination with rails having recesses between the wheel engaging portion and the base position, of an integral one piece connector therefor having opposed rail receiving sockets and a web separating said sockets and disposed below said wheel engaging portions thereby to enable said rails to abut against each other, the inner side of said sockets being open thereby to permit the connector to be disengaged from the rails by outward movement transversely therefrom.

In testimony whereof, I have hereunto signed my name to this specification.

NICK SOLTESZ.
